COMBINED OPEN HOPPER PUMP AND BASE OR SIMILAR ARTICLE

Frank W. Fernholtz, Van Nuys, Calif., assignor to Fernholtz Manufacturing Company, Los Angeles, Calif., a corporation of California

Filed Sept. 8, 1964, Ser. No. 81,623

Term of patent 14 years

(Cl. D65—1)

FIG. 1.

FIG. 2.

FIG. 3.

FIG. 4.

FIG. 5.

FIG. 6.

FIGURE 1 is a perspective view of a combined open hopper pump and base or similar article, showing my new design;

FIGURE 2 is a side view thereof;

FIGURE 3 is a right end elevational view thereof;

FIGURE 4 is a top plan view thereof;

FIGURE 5 is an elevational view of the side opposite that shown in FIGURE 2; and

FIGURE 6 is a left end elevational view thereof.

I claim:

The ornamental design for a combined open hopper pump and base or similar article, as shown.
